UNITED STATES PATENT OFFICE.

JAMES EARLE PERCY, OF HOOSICK FALLS, NEW YORK, ASSIGNOR OF THREE-FIFTHS
TO CARL H. GETTY AND AARON W. SHERWOOD, OF HOOSICK FALLS, NEW YORK.

CLOSURE FOR MILK-BOTTLES.

1,091,761.

Specification of Letters Patent. Patented Mar. 31, 1914.

Application filed June 13, 1913. Serial No. 773,386.

To all whom it may concern:

Be it known that I, JAMES EARLE PERCY, a citizen of the United States, residing at Hoosick Falls, county of Rensselaer, and 5 State of New York, have invented certain new and useful Improvements in Closures for Milk-Bottles, of which the following is a specification.

The invention relates to such improvements and consists of the novel construction hereinafter described and subsequently claimed.

Reference may be had to the accompanying drawings, and the reference characters marked thereon, which form a part of this specification. Similar characters refer to similar parts in the several figures therein.

Figure 1 of the drawings is a plan view of a closure for milk-bottles and the like embodying my invention in preferred form. Fig. 2 is a view in perspective of the neck-portion of a milk-bottle, showing the closure applied thereto to seal the bottle. Fig. 3 is a view in perspective of the closure detached, with the spout open. Fig. 4 is a 20 side view of the closure detached, with the spout open. Fig. 5 is a view in perspective, showing the neck of a bottle provided with my improved closure with the spout open 25 as in pouring milk from the bottle. Fig. 6 is a plan view of a blank of flexible material from which the disk is formed, before the same is folded to disk-form. Fig. 7 is 30 a cross-section of the closure taken on the broken line 7-7 in Fig. 1, on an enlarged scale. Fig. 8 is a plan view of a closure embodying my invention in a modified form. Fig. 9 is a view in perspective of the same 35 with the spout open. Fig. 10 is a plan view 40 of the blank adapted to be folded to disk-form in carrying out my invention as shown in Fig. 8.

The principal object of the invention is 45 to provide a sealing-closure for milk-bottles and the like, having as a constituent part thereof a folded spout-portion connected along its mouth-end with the body of the closure by a weakened line of fracture, and adapted when separated from the body-portion 50 along said line of fracture to be unfolded and opened out to form a spout through which the contents can be poured from the bottle.

Referring to Figs. 1 to 7 inclusive, where- 55 in my invention is shown in preferred form,

the blank shown in Fig. 6 is adapted to be folded along the convergent lines 1-1 and the convergent lines 2-2, the closure being thus caused to assume disk-form with a tapered box-plait, 3, extending from one edge 60 diametrically across the disk.

The closure is provided with a weakened line of fracture, 4, extending transversely across a wider portion of the outer member of the plait, and with weakened lines of 65 fracture, 5-5, extending from the respective ends of the line 4 transversely of the respective inner members of the plait.

It will be understood that the sheet of 70 flexible material of which the closure is made, is so scored or otherwise weakened along the respective lines of fracture 4 and 5, so that it can be readily broken or severed along said lines to separate that part of the plait nearer the center of the closure along 75 said lines from the body-portion of the closure, permitting the plait to be unfolded or opened out to the form shown in Figs. 3, 4, and 5 to form a spout 3a through which the 80 contents of the bottle can be poured.

The closure is provided with a crease, 6, along the longitudinal middle of the outer member of the plait, intersecting the line of fracture, 4, which facilitates the opening 85 out of the spout to the form shown in Figs. 3, 4, and 5.

To facilitate maintaining the spout in open position the lines of fracture, 5-5, are extended slightly farther away from the center of the disk than the line of fracture, 4, so that as the spout is opened out, the edges of the spout formed on the inner members of the plait by the lines, 5-5, wedge and bind against the edge formed by the line, 4, on the body-portion of the closure as 90 shown in Fig. 3.

If it is not desired to pour out all of the 95 contents of the bottle at once, after the desired quantity has been poured the spout can be folded and pressed back into substantially its original position, the edges of the mouth of the spout and the body-portion of the closure meeting quite closely along the lines 4 and 5, so that while the closure may not thereafter be absolutely 100 water-tight, it serves to effectively close the bottle and to exclude dust and dirt therefrom.

The closure is preferably coated with par- 105 affin, wax or the like, and its plaited portions 110

particularly along the edge of the disk are compressed, so that they are reduced in thickness and held together by the paraffin, the edge thus treated being adapted to 5 tightly fit within the mouth of the bottle.

While I have shown in Fig. 6 a blank adapted to be folded up to circular or disk form, it will be apparent that a sheet of flexible material of indefinite shape can be 10 plaited in the form described and a disk afterward stamped or cut therefrom of the desired size.

The closure may be made of any flexible material having sufficient strength and body 15 to meet the conditions of use, as heavy paper or the like.

In Fig. 10, I have shown a blank adapted to be folded along the lines, 8 and 9, to form a single plait, 10, as shown in Fig. 8, and 20 provided with weakened lines of fracture, 11, in the outer member of the plait and 12 in the inner member of the plait, extending transversely across a wider portion of the plait and provided with creases or fold-lines, 13 and 14, whereby when the plaited portion is severed along the lines 11 and 12, it can be unfolded and opened out to the 25 position shown in Fig. 9, forming a spout 10^a with a square mouth.

30 The size of the disk and the configuration of its edge-portion may be varied to adapt the closure for the bottle with which it is to be used.

The closure unbroken along the weakened 35 lines of fracture is inserted tightly in the mouth of the bottle to seal the same until such time as it is desired to remove part or all of the contents of the bottle, whereupon it is broken or severed along said lines 40 of fracture by means of a knife or other instrument, permitting the spout to be unfolded and opened out as above described.

What I claim as new and desire to secure by Letters Patent is—

45 1. A closure for milk-bottles and the like, comprising a disk-shaped body of flexible material having a plait formed with transverse weakened lines of fracture defining the mouth of a spout-shaped portion thereof.

50 2. A closure for milk-bottles and the like, comprising a disk-shaped body of flexible material having a tapered plait formed with weakened lines of fracture extending transversely across a wider portion of the plait 55 defining the mouth of a spout-shaped portion thereof.

3. A closure for milk-bottles and the like,

comprising a disk-shaped body of flexible material having a box-plait formed with a central, longitudinal crease and with transverse weakened lines of fracture defining the mouth of a spout-shaped portion thereof. 60

4. A closure for milk-bottles and the like, comprising a disk-shaped body of flexible material having a tapered box-plait formed 65 with a central, longitudinal crease and with transverse weakened lines of fracture across a wider portion of the plait defining the mouth of a spout-shaped portion thereof.

5. A closure for milk-bottles and the like, comprising a disk-shaped body of flexible material having a plait formed with transverse weakened lines of fracture defining the mouth of a spout-shaped portion thereof, said line of fracture of the inner member of the plait extending away from the center of the disk to a greater degree than the line of fracture of the outer member of the plait. 75

6. A closure for milk-bottles and the like, comprising a disk-shaped body of flexible material having a plait extending convergently from one edge of the disk formed with transverse weakened lines of fracture defining the mouth of a spout-shaped portion 80 thereof. 85

7. A closure for milk-bottles and the like, comprising a disk-shaped body of flexible material having a tapered box-plait extending from one edge of the disk diametrically 90 across the disk formed with transverse weakened lines of fracture defining the mouth of a spout-shaped portion thereof.

8. A closure for milk-bottles and the like, comprising a disk-shaped body of flexible material having a plait formed with transverse weakened lines of fracture defining the mouth of a spout-shaped portion thereof, the members of said plait being of reduced thickness along the edge of the disk 100 and held together by paraffin or the like.

9. A closure for milk-bottles and the like, comprising a disk-shaped body of flexible material having as a constituent part thereof a folded spout connected with the body of 105 the closure by a weakened line of fracture along the mouth-portion of the spout.

In testimony whereof, I have hereunto set my hand this 31st day of May, 1913.

JAMES EARLE PERCY.
